[57] CLAIM

The ornamental design for a personnel and material carrying trailer, substantially as shown.

DESCRIPTION

FIG. 1 is a front elevational view of a personnel and material carrying trailer showing our new design; the rear being a mirror image thereof;

FIG. 2 is a top plan view thereof;

FIG. 3 is a side elevational view thereof, the opposite side being a mirror image of the side shown herein.

FIG. 1.

FIG. 2.

FIG. 3.
